UNITED STATES PATENT OFFICE.

JOSÉ JOAQUIN DE SILVA, OF GUANAJUATO, GUANAJUATO, MEXICO.

CHAIN-PUMP.

SPECIFICATION forming part of Letters Patent No. 380,425, dated April 3, 1883.

Application filed November 18, 1887. Serial No. 255,527. (No model.) Patented in Mexico March 5, 1887.

To all whom it may concern:

Be it known that I, JOSÉ JOAQUIN DE SILVA, a citizen of the Republic of Mexico, and a resident of the city of Guanajuato, in the State of 5 Guanajuato, Republic of Mexico, have invented an Improvement in Chain-Pumps, of which the following is a specification.

My invention relates to that class of chain-pumps in which a series or chain of connected 10 buckets are combined with a supporting and operating wheel by which the buckets are continuously immersed, raised, and discharged of their contents.

My present invention relates more especially to the construction of the wheel, with a 15 view to combine both a saving of practically all of the water raised with rapidity of delivery, and simplicity of construction, cheapness, and durability of the wheel.

20 My invention belongs to those wheels in which the water is delivered from the buckets into a series of canals formed in the periphery of the wheel, which canals are so constructed as to immediately deliver at the side of the 25 wheel the water so received and discharge it into a suitable receptacle or duct. While waste is thus practically done away with, the water is discharged from the wheel at the earliest possible moment, thus relieving the apparatus 30 of weight and saving power.

In order to make my invention more clearly understood I have shown in the accompanying drawings a means for carrying it into effect.

In said drawings Figure 1 is a perspective view of so much of a chain-pump as is necessary for the illustration of my invention. Fig. 35 2 is a vertical sectional view of the wheel detached. Fig. 3 is a side elevation showing another arrangement of the receiving-duct.

40 Referring to the drawings, D D' indicate two peripheral edge flanges, one at each side of the wheel. They are supported by two spiders, A A', carried in turn by the main shaft E, to which latter the actuating-power may be applied. The flanges D D' may be connected 45 with each other in any suitable manner which will give the necessary rigidity to the structure. In the wheel illustrated transverse braces a, parallel with the axis of the wheel, extend 50 from one flange to the other, into both of which they are mortised.

The canals already referred to are shown at B. They are arranged around the periphery of the wheel, and are constructed on lines inclined relative to its axis. This inclination 55 of the ducts causes the water, as soon as it is received from the buckets, to be directly discharged at the side of the wheel.

I have shown in the drawings the best manner known to me for constructing the said 60 canals, though other suitable methods may be employed without departing from my invention. F indicates a peripheral partition which is at all points inclined relative to the axis of the wheel—that is to say, it constitutes the 65 surface of a frustum of a cone, by which term I would include also the analogous shape of a pyramid. To this partition are jointed at intervals corresponding, preferably, to the distance between buckets on the chain substantially-radial partitions f, which are also secured to the flanges D D'. The partition F upon one edge joins the inner surface of one of these flanges—in the drawings the flange D—while the other edge is inside of the inner 70 periphery of the flange D'. The canals B are thus closed at their higher ends and provided at their lower ends with discharge-openings. By placing the partitions f under the braces a the overhanging edges of the latter are utilized 75 to prevent the escape of water from the canals by splashing.

At that side of the wheel to which the canals B discharge is arranged a suitable receptacle or duct, C. Its shape or position is not material, so long as it is in proximity to the openings from the canals and catches accurately 80 their discharge. It may be arranged concentrically with the wheel, as shown in Fig. 3, by which means the fall of the water is shortened 90 and it may be caught more accurately.

G indicates the series of buckets connected by the rope or chain H, or jointed together in any approved manner.

The operation of the device is as follows: 95 Power having been applied to the wheel to rotate it in the proper direction, the buckets will ascend, (upon the right hand of Fig. 1,) and immediately after passing above the horizontal plane of the axis of the wheel will discharge 100 into the canals B. The water thus received by the canals is immediately transferred to

the duct C and the apparatus relieved of its weight.

Having thus described my invention, what I claim, and desire to secure by Letters Patent of the United States, is—

1. In a chain-pump, the combination, with a series of connected buckets, of a wheel adapted to support the same, said wheel having two parallel frames or spiders, a continuous peripheral partition, F, in the shape of a frustum of a cone, inclined to the axis of the wheel, and substantially-radial partitions meeting the former partitions and forming therewith inclined canals, substantially as described.

2. In a chain-pump, the combination, with a wheel provided upon its periphery with inclined canals, of a receiving-duct arranged in an arc substantially concentric with the wheel and situated in proximity to the discharge-openings of the canals, substantially as described.

JOSÉ JOAQUIN DE SILVA.
